SPRAY DEVICE FOR WASHING MACHINES

Frank G. Walker, Minneapolis, Minn.

Application January 13, 1950, Serial No. 138,344

8 Claims. (Cl. 299—69)

1

This invention relates to improvements in a spray device for a washing machine and, more particularly, for a dish washing machine. The invention especially lends itself to the efficient washing of large culinary and baking articles such as steam table, baking and roasting pans. However, the use thereof is not restricted to dish washing machines adapted for washing such specifically enumerated culinary articles.

Considerable difficulty has been experienced heretofore in providing an efficient and easily operable bearing for the rotatable spray head of a dish washing machine. One difficulty has been that bearings heretofore used develop a considerable amount of friction during operation. Therefore, if the spray head and bearing were designed so that rotation thereof could be readily started, the speed of rotation of the spray head during normal operation was too great to produce desirable washing efficiency.

Another difficulty has been that, if the bearings were mounted internally of the water distributing means, grit and other entrained abrasive materials within the washing solution would become lodged between the relatively moving surfaces of the spray head and bearing and would either impair the bearing surface so as to cause leakage or cause additional friction and retard the operating speed of the spray head.

Still another difficulty has been that, if for any purpose it was desired to remove the rotatable spray head so as, for example, to repair it or interchange it for a different type of spray head, it has heretofore been necessary to disassemble a considerable amount of the bearing structure in order to free the spray head from its bearing so as to be able to replace either the same head or another one within said bearing.

It is an object of the present invention to overcome these difficulties by providing an extremely simple and durable rotatable spray head and a supporting bearing therefor, said bearing being constructed so as to present a minimum amount of friction, whereby the rotation of the spray head can easily be started when water pressure is furnished thereto, and the operating rotational speed of the head is as slow as desired for efficient dish or utensil washing.

Another object of the invention is to provide yieldable sealing means between the relatively movable parts of the rotatable spray head and its bearing, said sealing means serving to accommodate grit or other abrasive material entrained in the washing solution in such a manner as not to score the surface of the bearing material.

2

and also permit yieldable engagement between the relatively moving parts of the spray head and its bearing so as to provide substantially water tight engagement between said moving parts.

Still another object of the invention is to so construct the rotatable movement of the spray head and its bearing so that the spray head may be removed from the bearing simply by lifting the spray head from the bearing, no other disconnection of any components of the spray head or bearing being required to accomplish such removal.

A still further object of the invention is to so construct the bearing and the rotatably supported portions of the spray head that, when the spray head is being rotated due to the force of the water being discharged therefrom, the head will substantially float relative to the bearing, thus minimizing the amount of force required to rotate the spray head and also reducing wear between the relatively moving surface of the spray head and its bearing.

Details of these objects and of the invention, as well as other objects thereof are set forth in the following specification and illustrated in the accompanying drawing comprising a part thereof.

In the drawing,

30 Figure 1 is a vertical side elevation of an exemplary dish washing machine embodying the principles of the present invention, part of said machine being broken away better to illustrate details of said invention.

35 Figure 2 is a top plan view of a rotatable manifold spray head positioned in its bearing and embodying the principles of the present invention.

Figure 3 is a side elevation, partly in section, 40 of the spray head and bearing shown in Fig. 2.

Figure 4 is a fragmentary side elevation of one of the spray nozzles or ports provided in the spray head illustrated in the other figures.

In the present illustration, an exemplary dish 45 washing machine has been illustrated, it being understood that the principles of the present invention may be readily applied to other types of dish washing machines than illustrated in Fig. 1. In Figure 1, the dish washing machine comprises 50 a casing 10 having a top 12 and a front opening 14 through which trays or racks 16 containing dishes or culinary articles, such as baking or steam table pans 18, may be placed within the casing 10 or removed therefrom. The rack 16 55 preferably is provided with suitable crossbars 20

which are arranged so as to hold the pans or other culinary articles or dishes positioned within the tray so as to be readily engaged by cleaning sprays projected upward against them. Any suitable means such as legs on the rack may be used to support the rack alone above the bottom of the casing 10.

While not shown in the present drawing, it is readily understood that the casing 10 may have suitable stationary or movable sprays mounted adjacent the top 12 thereof, whereby cleansing sprays may be discharged against the uppermost surface of the dishes or culinary articles held within the rack 16. In many types of conventional dish washing machines, these top sprays are stationary since, usually, the bottoms of dishes or culinary articles such as pans do not require as much washing as the interior thereof as the bottoms of the dishes and pans are seldom extensively soiled. Hence, the major amount of washing function is directed to the interior of the dishes or pans when held within the racks 16 in the exemplary manner illustrated in Fig. 1.

It is also to be understood that the washing solution sprayed against the articles within the rack 16 drains into a suitable sump, not shown, in the lower part of the machine and from here it is usually recirculated by a suitable pump, also not shown, in accordance with the conventional practice so as to economize on the use of hot water and cleansing agents.

In the exemplary illustration shown in the drawing, the spray directed against the interiors of pans 18 are produced by the following mechanism. A supply pipe 22 is connected with a suitable pump, not shown, for purposes of feeding washing solution, under considerable pressure, to the spraying mechanism to be described. If desired, the supply pipe 22 may also be used to feed overhead sprays in the upper portion of the casing 10. A horizontal pipe 24 which supports the spray mechanism described hereinafter is connected to supply pipe 22.

Connected to the outer end of the pipe 24, substantially centrally below the rack 16 when positioned in operative position within the casing 10, is a hollow first T head 26, details of which are shown especially in Fig. 3. The stem 28 of said T head is directly connected to pipe 24 and the transverse head of the T 26 has a passage 30 extending therethrough as clearly shown in Fig. 3. The passage 30 is preferably disposed with its axis in a vertical operating position. The upper end 32 of the T head 26 comprises a thrust bearing for purposes to be described. The lower end of the T head 26 is preferably slightly constricted on its interior surface so as to provide a cylindrical bearing surface 34 having a somewhat smaller diameter than the interior bearing surface 36 at the upper end of the T head 26.

Rotatably supported within the upper end of the first T head 26 is a second T head or T manifold 38, the stem 40 of which is rotatably mounted within the upper end of T head 26 as clearly shown in Fig. 3. Said stem is also provided with an annular laterally projecting flange 42 arranged rotatably to engage the upper end 32 of T head 26, especially when the manifold T 38 is not being rotated. The stem 40 of the T manifold 38 is also provided with an annular groove 44 which receives a resilient collar 46 that is preferably formed from good quality natural or synthetic rubber such as "Neoprene."

The outer diameter of the collar 46 closely conforms to the diameter of the interior bear-

ing surface 36 of T head 26, whereby the T manifold 38 may readily rotate relative to the T head 26 without producing any substantial friction, especially when the rubber becomes wet during use. The wet rubber will substantially eliminate any friction between the closely conforming surface of the collar and interior bearing. Further, the yieldable collar 46 will function to permit grit or other abrasive material entrained within the washing solution to become embedded within the rubber so as to materially reduce, if not completely eliminate, any possibility of any grit or abrasive material scoring the bearing surface 36. It has also been found that the water applied under pressure against the lower portion of the collar 46 will serve to spread said collar outwardly into closely sliding, but substantially frictionless, engagement with the bearing surface 36 when the collar 46 is wet during use. Thus, an effective seal is provided between the T manifold 38 and the upper end of T head 26.

A pistonlike closure 48 is rotatably mounted within the bearing 34 in the lower end of T head 26. The closure 48 is also provided with an annular groove 50 in which is seated a collar 52 formed from material and functioning similarly to the collar 46. The closure 48 is fixed to the T manifold 38, so as to be rotatable therewith, by any suitable means such as a rod 54. When water is introduced to the T head 26 through the stem 28 thereof, water pressure will be exerted against the inner surface of closure 48 and water will also travel upwardly through the upper end of the T head 26 in a direction opposite to the force exerted against closure 48, through the stem 40 of manifold T 38, and in opposite directions into the branches 56 of the manifold T 38 as clearly shown by direction arrows in Figure 3.

As has been stated above, the diameter of bearing surface 34 is less than that of bearing surface 36. Similarly the outer diameter of the closure 48 and collar 52 thereon is less than the outer diameter of stem 40 and collar 46 thereon. The difference in diameters is such that the pressure exerted against the inner surface of closure 48 will approximately equal or be very slightly greater than the force exerted by the water in passing upward through stem 40 of manifold T 38. Under these conditions, the manifold T 38 will substantially float relatively to the T head 26 and, the aforementioned diameters can be so related for any given pressure of water entering the stem 28 of T head 26 that the flange 42 of manifold head 38 will barely engage the upper end 32 of T head 26 when the spray head, comprising manifold T 38 and spray arms 58 connected to the branches 56 of said manifold T 38, is rotated.

Inasmuch as the bearing surface 36 is either equal to or preferably greater than the bearing surface 34 in T head 26, it will be seen that the manifold T 38 and its assembled spray arms 58 may be removed quickly and readily from the T head 26 merely by lifting the manifold T 38 axially of the passage 40 and through the bearing 36, without requiring any other disassembly or manipulation of any of the components of the entire device.

Each of the spray arms 58 is provided with a plurality of spray discharge ports 60 which are formed so as preferably to discharge a vertical spray which will flare out to a certain extent as shown in Fig. 1. Spray from these ports will, for example, primarily be directed against the

highest portions of the interiors of the pans 18, for example, as the manifold T 38 rotates. Each arm is also provided substantially centrally thereof with an outlet nozzle 62, details of which are best shown in Fig. 4. Spray ports 64 are formed in opposite sides of nozzles 62 and the axes of the ports 64 are such that they will discharge sprays angularly spaced apart, for example, as much as 135°, whereby they are directed against the lowermost edges and interior portions of the pans 18 as shown in Fig. 1. These ports may also extend at a slight angle to one side of a vertical plane through arms 58 in a manner to rotatably drive the spray head about its vertical axis. The nozzles 62 are also each provided with a spray port 66 which extends at a slight angle from the vertical axis of the nozzle 62, the axis of the port 66 in one nozzle 62, however, being inclined oppositely to the axis of the port 66 in the other nozzle 62 so as to cause rotation of the spray head about the axis of passage 30. Thus, if one of the ports 64 or 66 should become momentarily clogged, the force of sprays from the other ports will rotate the spray head.

In view of the limited amount of friction existing between the manifold T 38 and T head 26, as well as between closure 48 and T head 26, the angle between the ports 66 and said vertical plane through the spray head need not be great for purposes of initiating rotation of the spray head relative to the T head 26 after the pump has been started for purposes of furnishing washing solution under pressure to the T head 26. After the spray head begins to rotate, the driving force exerted by the sprays exiting through the various ports 64 and 66 will serve to rotate the spray head comprising manifold T 38 and arms 58 at a relatively slow speed, such speed however being determined by the angles between said ports and a vertical plane through the spray head. Sprays 60 may be partially intersected by the sprays from ports 64 and thereby create a partially somewhat turbulent spray which will serve to thoroughly cleanse the interior surface of dishes or culinary articles against which the sprays are directed as the spray head rotates.

Culinary articles such as steam table, baking or roasting pans frequently have food materials such as gravy more or less thickly accumulated on and firmly adhering to the surfaces of such pans, and particularly the interior thereof, whereby it is generally difficult to thoroughly cleanse such firmly adhered substances from the surface of said pans. In order to facilitate the cleansing of such pans, it has been found advantageous to apply spray solutions at considerably higher pressures than is normally used in conventional dish washing machines. Thus, when washing culinary articles such as the pans referred to above, it has been found that such pans are washed satisfactorily when using washing solutions delivered to the spray head at pressures of between 20 and 30 pounds per square inch, or even as high as 35 pounds per square inch. The structure described and illustrated herein readily is capable of utilizing washing solutions furnished at such pressures and the functioning of the device under such pressures is as described herein above.

It will be seen from the foregoing that the present invention provides an extremely simple, inexpensive and durable spray head for a washing machine adapted to wash dishes and various types of culinary articles other than dishes such as cooking utensils and steam table, baking and

roasting pans. The rotatable spray head may be easily and quickly removed and replaced without requiring the manipulation or separation of any components of the device prior to removing the spray head from its bearing by a simple lifting operation. An inexpensive, yet highly effective sealing means is provided between the relatively movable surfaces of the spray head and the T head within which the manifold type spray head rotates, said sealing means also serving to permit grit and particles of other abrasive material to become embedded therein so as to prevent scoring the metallic bearing surface of the T head which rotatably supports the spray head. Said sealing means is also inexpensive and may be quickly and easily replaced when worn beyond further use. However, in view of the fact that such sealing means affords substantially no friction relative to the metallic bearing surface of the supporting T head when rotating relative thereto while wet under actual conditions of operation, wear of such sealing material occurs very slowly. The manifold spray head of the device is also provided with a pistonlike closure means which serves to maintain the spray head in rotatable operative position and the spray pressures developed within the supporting T head of the device are such that they substantially balance each other in opposite directions so as to provide a floating action between the spray head and the T head rotatably supporting the same. The construction is also such that rotation of the spray head is easily started and the speed of rotation of the head during operation is relatively slow so as to produce a highly effective spraying action for cleaning the surface of dishes and other culinary articles while the spray head moves relative to the same during the rotation of the spray head.

40 While the invention has been illustrated and described in its preferred embodiment and has included certain details, it should be understood that the invention is not to be limited to the precise details herein illustrated and described 45 since the same may be carried out in other ways, falling within the scope of the invention as claimed.

I claim as my invention:

50 1. A spray device for a washing machine comprising a hollow T positioned with its head extending substantially vertically and its stem connectible with a water supply, a spray arm provided intermediately of its ends with a laterally projecting inlet rotatably mounted axially of 55 and communicating with the upper end of the head of said T, said spray arm being provided with spray discharge ports arranged to rotatably drive said arm as spray is discharged therefrom, and a piston-like closure rotatably mounted 60 within the lower end of the head of said T and fixed to said spray arm for rotation therewith relative to said head of said T.

65 2. A spray device for a washing machine comprising a head having a water passage extending therethrough and a water inlet intersecting said passage intermediately of the ends thereof, a hollow T having its stem rotatably communicating with one end of said passage, spray arms 70 projecting in opposite directions to each other from the branches of said T, said spray arms being provided with spray discharge ports arranged to rotatably drive said T as spray is discharged therefrom, and a closure for said passage rotatably mounted therein adjacent the oth-

er end thereof and fixed to said T for rotation therewith relative to said head.

3. A spray device for a washing machine comprising a head having a water passage extending therethrough and a water inlet intersecting said passage intermediately of the ends thereof, a hollow T having its stem rotatably extending within and communicating with one end of said passage, spray arms projecting in opposite directions to each other from the branches of said T, said spray arms being provided with spray discharge ports arranged to rotatably drive said T as spray is discharged therefrom, a piston-like closure for said passage rotatably mounted therein adjacent the other end thereof and fixed to said T for rotation therewith relative to said head, and a yieldable collar surrounding said closure and rotatably engaging the inner surface of said passage.

4. A spray device for a washing machine comprising a head having a water passage extending therethrough and a water inlet intersecting said passage intermediately of the ends thereof, a hollow T having its stem rotatably extending within and communicating with one end of said passage of said head, a laterally projecting flange on said stem rotatably engageable with said head, spray arms projecting in opposite directions to each other from the branches of said T, said spray arms being provided with spray discharge ports arranged to rotatably drive said T as spray is discharged therefrom, a piston-like closure for said passage rotatably mounted therein adjacent the other end thereof and fixed to said T for rotation therewith relative to said head, and yieldable collars surrounding said stem of said T and said closure, said collars rotatably engaging the inner surface of said passage to prevent the passage of any appreciable amount of water between said surface and collars.

5. A spray device for a washing machine comprising a head having a water passage extending therethrough and a water inlet intersecting said passage intermediately of the ends thereof, a hollow T having its stem rotatably extending within and communicating with one end of said passage of said head, a laterally projecting flange on said stem rotatably engageable with said head, spray arms projecting in opposite directions to each other from the branches of said T, said spray arms being provided with spray discharge ports arranged to rotatably drive said T as spray is discharged therefrom, a piston-like closure for said passage rotatably mounted therein adjacent the other end thereof and fixed to said T for rotation therewith relative to said head, said closure and stem of said T having annular grooves in the perimeters thereof, and renewable yieldable collars disposed within said grooves, said collars rotatably engaging the inner surface of said passage to prevent the passage of any appreciable amount of water between said surface and collars.

6. A spray device for a washing machine comprising a head having a water passage extending therethrough and a water inlet intersecting said passage intermediately of the ends thereof, a hollow T having its stem rotatably extending

within and communicating with one end of said passage of said head, a laterally projecting flange on said stem rotatably engageable with said head, spray arms projecting in opposite directions to each other from the branches of said T, said spray arms being provided with spray discharge ports arranged to rotatably drive said T as spray is discharged therefrom, a piston-like closure for said passage rotatably mounted therein adjacent the other end thereof and fixed to said T for rotation therewith relative to said head, and yieldable collars surrounding said stem of said T and said closure and rotatably engaging the inner surface of said passage to prevent the passage of any appreciable amount of water between said surface and collars, the diameter of said closure being no greater than the outer diameter of said stem of said T, whereby said T and spray arms may readily be removed as a unit from said head axially of said one end of said passage thereof.

7. A spray device for a washing machine comprising a head having a water passage extending therethrough and a water inlet intersecting said passage intermediately of the ends thereof, the inner diameter of said passage being smaller at one end than the other, a hollow T having its stem rotatably extending within and communicating with the end of said passage having the larger diameter, spray arms projecting in opposite directions to each other from the branches of said T, said spray arms being provided with spray discharge ports arranged to rotatably drive said T as spray is discharged therefrom, and a piston-like closure for said passage rotatably mounted within the end thereof having the smaller diameter and fixed to said T for rotation therewith relative to said head.

8. A spray device for a washing machine comprising a first hollow T having its stem connectible with a water supply and its head extending substantially vertically in operative position, a second hollow T having its stem rotatably extending within and communicating with the upper end of the head of said first T, a flange surrounding the stem of said second T rotatably engaging said upper end of said head, spray arms projecting in opposite directions from the ends of the head of said second T and provided with water discharge ports arranged to rotatably drive said second T and arms about the axis of said first T as spray is discharged from said ports, and a piston-like closure rotatably mounted within the lower end of the head of said first T and fixed to said second T for rotation therewith relative to said head of said first T.
